(57) **CLAIM**

The ornamental design for a wheel as shown and described.

DESCRIPTION

FIG. 1 is a front perspective view of a wheel; FIG. 2 is a rear perspective view of the wheel of FIG. 1; FIG. 3 is a front view of the wheel of FIG. 1; FIG. 4 is a rear view of the wheel of FIG. 1; and, FIG. 5 is a side view of the wheel of FIG. 1, wherein the top and bottom views of the wheel of FIG. 1 are identical and the opposite side view of the wheel of FIG. 1 is a mirror image thereof.

All broken lines illustrate subject matter, structure, and/or features of the wheel that form no part of the claimed design. The dot-dash broken lines illustrate the bounds of the claim and form no part of the claimed design.

1 Claim, 5 Drawing Sheets(56)
